RAZOR TRAY

Richard J. Petrillo, Norwell, Mass., assignor to
The Gillette Company, Boston, Mass.

Filed Jan. 22, 1974, Ser. No. 435,536

Term of patent 14 years

Int. Cl. D9—03

U.S. Cl. D9—186

Fig. 1

Fig. 2

Fig. 3

Fig. 4

Fig. 5

Fig. 6

Fig. 7

FIG. 1 is a perspective view of a razor tray showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and

FIG. 7 is a rear elevational view thereof.

I claim:

The ornamental design for a razor tray, substantially as shown.
